Primary Examiner — Michael A Pratt(74) *Attorney, Agent, or Firm* — Stoel Rives LLP; Robert R. Teel(57) **CLAIM**

We claim the ornamental design for a sighting device, as shown and described.

DESCRIPTION

FIG. 1 is an isometric view showing an eyepiece end of a sighting device.

FIG. 2 is an isometric view showing an objective end of the sighting device.

FIG. 3 is an eyepiece-end elevation view of the sighting device.

FIG. 4 is an objective-end elevation view of the sighting device.

FIG. 5 is a left side elevation view of the sighting device.

FIG. 6 is a right side elevation view of the sighting device.

FIG. 7 is a top plan view of the sighting device; and,

FIG. 8 is a bottom plan view of the sighting device.

In the drawing figures, the broken lines are illustrative of portions of the article that form no part of the claimed design.

1 Claim, 5 Drawing Sheets(56)
